(57) **CLAIM**

The ornamental design for a blood glucose meter, as shown and described.

DESCRIPTION

FIG. 1 is a front view of a blood glucose meter comprising a new, original and ornamental design;

FIG. 2 is a rear view of a blood glucose meter comprising the new, original and ornamental design;

FIG. 3 is a left-hand side view of a blood glucose meter comprising the new, original and ornamental design;

FIG. 4 is a top view of a blood glucose meter comprising the new, original and ornamental design;

FIG. 5 is a front view of a blood glucose meter, shown in an open position, comprising the new, original and ornamental design;

FIG. 6 is a rear view of a blood glucose meter, shown in an open position, comprising the new, original and ornamental design; and,

FIG. 7 is a left-hand side view of a blood glucose meter, shown in an open position, comprising the new, original and ornamental design.

The portions of the blood glucose meter shown in broken lines form no part of the claimed design.
